UNITED STATES PATENT OFFICE.

CHARLES E. BEDAUX, OF CLEVELAND, OHIO.

SAFETY-FENDER FOR VEHICLES.

1,386,308.

Specification of Letters Patent.

Patented Aug. 2, 1921.

Application filed April 8, 1921. Serial No. 459,584.

To all whom it may concern:

Be it known that I, CHARLES E. BEDAUX, a citizen of the United States, residing at Cleveland, in the county of Cuyahoga and 5 State of Ohio, have invented new and useful Improvements in Safety-Fenders for Vehicles, of which the following is a specification.

The present invention relates to safety 10 fenders for vehicles, as automobiles; and its object is to provide an improved fender of that character which may be readily and effectively operated; and further, to provide such a fender which in its inoperative position 15 may be compact and inconspicuous in appearance.

This and any other objects hereinafter appearing are attained by, and the invention finds preferable embodiment in, the structure 20 or structures hereinafter particularly described and illustrated by the accompanying drawings, in which:—

Figure 1 is a side view of the front portion 25 of an automobile equipped with my safety fender shown in operative position;

Fig. 2 is a front view of the same;

Fig. 3 is a plan view of my fender (in inoperative position) and of its casing, one of 30 the covers whereby an opening in the casing is closable being shown in open position;

Fig. 4 is a front view of the same, the other cover for closing such opening being shown in open position;

Fig. 5 is a plan view of a portion of the 35 same, showing the mountings of a pair of swingable arms and the springs whereby such arms are swung into diverging or operative position;

Fig. 6 shows one of the swingable arms 40 provided with means for holding it in operative position;

Fig. 7 is a transverse sectional view of the 45 casing and contained parts taken on a vertical plane corresponding to line 7—7 of Fig. 3;

Fig. 8 is a like view taken on a vertical plane corresponding to line 8—8 of Fig. 3;

Fig. 9 is a like view taken on a vertical 50 plane corresponding to line 9—9 of Fig. 3;

Fig. 10 is a plan view, partly in longitudinal section, of the casing and contained and connected parts, showing a modified construction whereby the arms may be swung;

Fig. 11 is a front view of a portion of the same; and

Fig. 12 is a transverse sectional view of parts thereof taken on a vertical plane corresponding to line 12—12 of Fig. 10.

In all the views except Figs. 1 and 2 the 60 flexible sheet 8 is omitted for the sake of clearness.

In the embodiments of the invention chosen for illustration by the drawings and for detailed description in the body of this 65 specification, my safety fender is carried at the front end of an automobile 1, being fastened thereto by suitable connections, as by the supporting members 2. The fender comprises a casing 3 extending horizontally, 70 and in the inoperative position of the mechanism resembling in appearance the ordinary front bumper or fender of an automobile. Pairs of arms 4, 5 are swingably mounted inside the casing, one pair adjacent 75 one side of the automobile and the other pair adjacent the automobile's other side, on pivot pins 6, 7 respectively, whose axes are inclined relatively to each other so that the arm 4 swings on its pivot pin 6 in an approximately vertical plane, and the arm 5 swings on its pivot pin 7 in a plane extending downwardly and outwardly from the front of the automobile. A strong flexible sheet 8 of suitable material, as heavy canvas, 85 is carried by the outer or free ends of these four arms, being secured at its corners thereto as by helical springs 9.

The arms 4, 5 of each pair may be swung outwardly from the casing into diverging 90 or operative position (shown in Figs. 1 and 2) by the leaf springs 10, 11 respectively, having orifices 12 near their free ends in which orifices the respective arms slidably engage in their swinging movement. Suitable 95 means, as the spring catches 13, 14 carried by the arms, (or some of them) are provided for securely holding such arms in their operative positions, the free extremities of the springs 13, 14 holdingly abutting 100 against the springs 10, 11, respectively, adjacent their orifices 12 as seen in Fig. 5.

The arms are held in inoperative or parallel position inside the casing, against the pressure of their operating springs 10, 11, 105 by releasable means, such means in the construction illustrated particularly in Fig. 7 being the bars 15, 16 swingably mounted at 17, 18 and holdingly engaging the arms 4 and 5 respectively. In moving these bars 110 to their arms-holding position seen in Fig. 7, the lower bar 16 is first swung into its

operative position whereupon the upper bar 15 is swung into its operative position, its extension 19 passing over or around the upper end 20 of the bar 16. The bars, being thus moved to their operative positions, are securely held therein by the bolt 21 pressed by its spring 22 into holding engagement with the orifice 23 in the end 20 of the bar 16. This bolt 21 being withdrawn from its holding engagement by the cord 24 against the pressure of the spring 22, first permits the upward movement of the bar 15 under the pressure of the springs 10 which swing the arms 4 upwardly; and when the free end 20 of the other bar 16 is thus released from the orifice 25 in bar 15, the bar 16 is permitted to move outwardly under the pressure of the springs 11 which swing the arms 5 forwardly. When the bars 15, 16 thus release the arms, their free ends under the pressure of their springs 10, 11 swing outwardly from the casing carrying the flexible sheet 8 (which has been folded into the casing with the swung-in arms) with them, and in so swinging press the bars 15, 16 against and swing open the covers 26, 27 swingably mounted at 28, 29 respectively and provided for closing the opening 30 in the upper and front sides of the casing, these covers when thus opened assuming the position seen in Fig. 1.

It will be understood that when the driver recognizes the probability of his automobile's colliding with pedestrian or other object in front of his machine, he instantly draws the cord 24 which extends to a position convenient for his grasping the same, whereupon the bars 15, 16 are released and the arms 4, 5 carrying the sheet 8 with them, swing out through the opening 30 in the casing and spread the sheet in such position, (shown in Figs. 1 and 2) as will receive and carry said object while the travel of the automobile is being stopped.

The parts in the position seen in Figs. 1 and 2, may be returned to inoperative position by swinging the arms 4, 5 and folding sheet 8 inwardly into the casing, moving the bars 15, 16 into holding engagement with said arms, and closing the covers 26, 27, whereupon the device resembles in appearance, the ordinary form of the front bumper of an automobile: By providing covers 26, 27 of sufficient rigidity and their mountings of sufficient strength, my fender in its inoperative position will function in like manner as such ordinary bumpers.

The arms 4, 5 may be swung outwardly into their operative positions by other means and mechanism than those above described: For instance, a cylinder 31 may be provided for each pair 4, 5 of arms, and have a piston 32 with connections between it and the arms for thus swinging them, as shown in Figs. 10, 11 and 12. Such connections are

desirably the connecting rod 33 pivoted to the piston 32 and to the lever 34 carried by the arm 5, and the toothed segment 35 of the arm 5 meshing with the toothed rack 36 pivotally and slidably connected at 39 to the lever 37 of the arm 4 to which arm said lever is connected by the pivot 40. The piston may be actuated by suitable pressure in the cylinder and when moved to swing the arms may be held in the arms' swung position by the releasable bolt 41 adapted to be engaged by the slot 42 in the keeper 43 on the piston, such keeper in the outward movement of the piston striking the inclined edge 44 of said bolt and moving it backwardly against the pressure of its spring 45.

The invention being intended to be pointed out in the claims, is not to be limited to or by details of construction of the particular embodiment thereof illustrated by the drawings or hereinbefore described.

I claim:

1. In a fender for vehicles; pairs of arms, the arms of one pair being swingably mounted respectively on relatively inclined axes adjacent one side of the vehicle and the arms of the other pair being similarly mounted adjacent the vehicle's other side; a flexible sheet carried by the free ends of the arms; means for swinging the arms of said pairs into diverging position.

2. In a fender for vehicles; pairs of arms, the arms of one pair being swingably mounted respectively on relatively inclined axes adjacent one side of the vehicle and the arms of the other pair being similarly mounted adjacent the vehicle's other side; a flexible sheet carried by the free ends of the arms; means for swinging the arms of said pairs into diverging position; releasable means for holding at least some of the arms in said position.

3. In a fender for vehicles; pairs of arms, the arms of one pair being swingably mounted adjacent one side of the vehicle and the arms of the other pair being swingably mounted adjacent the vehicle's other side, one arm of each pair being swingable in an approximately vertical plane and the other arm of each pair being swingable in a plane extending downwardly and outwardly from the fender-carrying end of the vehicle; a flexible sheet carried by the free ends of the arms; means for swinging the arms of said pairs into diverging position.

4. In a fender for vehicles; pairs of arms, the arms of one pair being swingably mounted adjacent one side of the vehicle and the arms of the other pair being swingably mounted adjacent the vehicle's other side, one arm of each pair being swingable in an approximately vertical plane and the other arm of each pair being swingable in a plane extending downwardly and outwardly from the fender-carrying end of the vehicle; a

- flexible sheet carried by the free ends of the arms; means for swinging the arms of said pairs into diverging position; releasable means for holding at least some of the arms 5 in said position.
5. In a fender for vehicles; a casing extending horizontally at the vehicle's end; pairs of arms, the arms of one pair being swingably mounted respectively on relatively inclined axes in the casing and adjacent one side of the vehicle, and the arms of the other pair being similarly mounted adjacent the vehicle's other side; a sheet carried by the free ends of the arms and foldable into the casing; means for swinging the arms of said pairs into diverging position wherein the sheet and the free ends of the arms are outside the casing; releasable means for holding the free ends of the arms in the 20 casing.
6. In a fender for vehicles; a casing extending horizontally at the vehicle's end; pairs of arms, the arms of one pair being swingably mounted respectively on relatively inclined axes in the casing and adjacent one side of the vehicle, and the arms of the other pair being similarly mounted adjacent the vehicle's other side; a sheet carried by the free ends of the arms and foldable into the casing; means for swinging the arms of said pairs into diverging position wherein the sheet and the free ends of the arms are outside the casing; releasable means for holding the free ends of the 25 arms in the casing; releasable means for holding at least some of the arms in their said diverging position.
7. In a fender for vehicles; a casing extending horizontally at the vehicle's end; pairs of arms, the arms of one pair being swingably mounted respectively on relatively inclined axes in the casing and adjacent one side of the vehicle, and the arms of the other pair being similarly mounted adjacent the vehicle's other side; a sheet carried by the free ends of the arms and foldable into the casing; means for swinging the arms of said pairs into diverging position wherein the sheet and the free ends 30 of the arms are outside the casing; swingably mounted bars adapted to releasably hold the arms in the casing; a bolt movable into and out of holding engagement with the bars in their arms-holding position.
- 55 8. In a fender for vehicles; pairs of arms, the arms of one pair being swingably mounted respectively on relatively inclined axes adjacent one side of the vehicle and the arms of the other pair being similarly mounted adjacent the vehicle's other side, the arms being swingable to diverging and to parallel positions; a flexible sheet carried by the free ends of the arms; means for 60 swinging the arms into diverging position; swingably mounted bars adapted to releasably hold the arms in parallel position; a bolt movable into and out of holding engagement with the bars in their arms-holding position.
9. In a fender for vehicles; a casing having an opening and extending horizontally at the vehicle's end; swingably mounted covers for said opening; pairs of arms, the arms of one pair being swingably mounted respectively on relatively inclined axes in the casing and adjacent one side of the vehicle, and the arms of the other pair being similarly mounted adjacent the vehicle's other side; a sheet carried by the free ends of the arms and foldable into the casing; means for swinging the arms of said pairs into diverging position wherein the sheet and the free ends of the arms pass through said opening to the outside of the casing; releasable means for holding the free ends 80 of the arms in the casing.
10. In a fender for vehicles; pairs of arms, the arms of one pair being swingably mounted respectively on relatively inclined axes adjacent one side of the vehicle and the arms of the other pair being similarly mounted adjacent the vehicle's other side; a flexible sheet carried by the free ends of the arms; springs pressing to swing the arms of said pairs into diverging position; releasable means for holding the arms 85 against the pressure of the springs.
11. In a fender for vehicles; pairs of arms; the arms of one pair being swingably mounted respectively on relatively inclined axes adjacent one side of the vehicle and the arms of the other pair being similarly mounted adjacent the vehicle's other side; a flexible sheet carried by the free ends of the arms; cylinders having pistons; connections between each piston and pair of arms for swinging said pair into diverging position by the movement of the piston.
12. In a fender for vehicles; pairs of arms, the arms of one pair being swingably mounted respectively on relatively inclined axes adjacent one side of the vehicle and the arms of the other pair being similarly mounted adjacent the vehicle's other side; a flexible sheet carried by the free ends of the arms; cylinders having pistons; connections between each piston and one arm of each pair and toothed segment and intermeshing toothed rack connections between said arm and the other arm of said pair for 100 swinging said pair into diverging position by the movement of the piston.
- In testimony whereof I have hereunto set my hand this 30 day of March, 1921.
